UNITED STATES PATENT OFFICE.

FREDERICK H. HEATH, OF MINNEAPOLIS, MINNESOTA, ASSIGNOR TO THE
HEATH RAIL JOINT COMPANY, OF SAME PLACE.

RAIL-JOINT.

SPECIFICATION forming part of Letters Patent No. 495,002, dated April 4, 1893.

Application filed May 28, 1892. Serial No. 433,955. (No model.)

To all whom it may concern:

Be it known that I, FREDERICK H. HEATH, of Minneapolis, in the county of Hennepin and State of Minnesota, have invented a certain Improved Rail-Joint, of which the following is a specification.

My invention relates to rail joints and supports and clamps therefor and its object is to provide a device of this class which will occupy a minimum weight and space in metal, which will possess a maximum strength to counteract the downward, lateral or torsional strains on the rail or rails, and finally which may be readily adjusted to any size rail with equal success.

To this end my invention consists in the combination with the tie-plate adapted to extend across and between adjoining ties and provided with depending trusses, of the rail or rails adapted to rest thereon, a pair of angularly formed rocker-clamps, a bolt extending transversely under the tie-plate for fastening said clamps, a separable angle-bar for one side of the rail and an integral angle-bar formed on the other side of the plate to engage the opposite side of the rail and having a gap or opening through which the clamps upon that side of the device projects into engagement with the flange of the rail or rails; and further in various details of construction and in combinations all as hereinafter described and particularly pointed out in the claims.

The invention will be more readily understood by reference to the accompanying drawings, in which:—

Figure 1 is a side elevation of a rail joint embodying my invention. Fig. 2 is a view of the other side thereof. Fig. 3 is an enlarged transverse section on the line $x-x$ of Fig. 2. Fig. 4 shows a plan view of the clamping jaws and bolt detached and as seen from beneath. Fig. 5 shows the clamping bolt, and, Figs. 6 and 7 are respectively side and sectional views of the washer which I employ.

As shown in the drawings, the rails 2, 2 are adapted to rest upon the plain upper surface of the long tie-plate 3 which in turn rests upon and is fastened to the tops of the cross ties 4. This plate is strengthened on its under side by the integral and depending trusses

shown, the same being made up of the vertical web 5, the diagonal extensions 6 thereof and the transverse trusses 7. The rails are aligned by the integral angle bar 8 extending up from the outer edge of the tie-plate and adapted to engage the webs only of the rails and fastened thereto by the bolts 9 which extend through large holes in the webs and are fastened on the separable angle bar 10 having the inclined upper edge 11 to engage the under side of the tread or ball of the rail and the long angle foot 12 to rest firmly upon the top of the rail base or flange. The lower edge 13 of the angle-bar rests upon the top of the tie-plate 3 which is extended to support the same. The rails are firmly clamped on the tie-plate by the longitudinally arranged curved clamps or rocker-jaws 14 and 15, each of which is strengthened by segmental ribs 16 and has two approaching clamp edges 18. The space between the clamping edges in each case is narrower than the opening in the inner part of the clamp. In order that the upper clamping edge of the block 14 may engage the base of the rail or rails directly I form the opening shown in the inclined part of the integral angle bar 8, the ends of this opening serving to prevent the slipping of the clamping block longitudinally. The clamp 15 is made larger than the other in order to take in the added thickness of the angle bar. The under side of each clamp is provided with a slot 20 and the outer side of each with a longitudinal seat 21, having the outwardly extended lower edge 22.

For securing the clamping blocks or jaws I employ the bolt 23 having the T-head 24 adapted to rest in the seat 21 of the clamp 15. The other end of the bolt is threaded to receive the nut 25 and a long washer 26 having the semicylindrical bearing surface or nib 27 and the flat face, and is inserted between the nut 25 and the seat 21 of the clamp 14, the bolt passing through a gap arranged in the web 5 beneath the tie-plate. It will be seen that when the clamping blocks are adjusted upon the rail and plate the lower edges 18 will project in beyond the upper edges of the jaws so that when the nut is tightened on the bolt the upper edges are drawn down firmly upon the tops of the rails with a con-

siderable leverage, thereby firmly securing the same in place. Owing to the cylindrical bearings employed between the bolt and the clamp the bolt will always occupy a level true position and exert its strength at the greatest advantage. It will be seen that the clamping blocks are prevented from slipping on the plates by the transverse trusses 7.

Having thus described my invention, I claim as new and desire to secure by Letters Patent—

1. The combination with the rails of the two angle-bars to engage opposite sides thereof, the two rocker-clamps having clamping edges 18 and each having a transverse slot in its lower side, and the draw-bolt extending beneath the rails and having its ends secured in said slots, as and for the purpose specified.

2. The combination with the rails, of the tie-plate whereon they rest, means for aligning the rails, the two rocker-clamps or blocks provided with the edges 18, the lower one of which bears upon the under side of said plate, and the transverse draw-bolt whereby said clamps are fastened, substantially as described and for the purpose specified.

3. The combination with the rails, of the tie-plate having the depending truss and the integral angle bar, said integral angle-bar provided with the gap or opening, the separable angle-bar, the smaller curved clamping block for the integral angle-bar side of the device, the larger clamp to engage the foot of said separable bar, and the lower side of said plate and the fastening bolt arranged beneath said plate, substantially as set forth.

4. The combination with the rails, of the tie-plate, the angle-bars, the curved clamping blocks, said clamping blocks provided with the longitudinal seats, the adjustable washer 40 pivoted in one of them, and the draw-bolt having a T-head seated in the other, substantially as described.

5. The combination with the rail or rails, of the tie-plate provided with the integral depending trusses, and the integral angle-bar having the gap described, the curved clamping blocks 14 and 15 having clamping edges 18, and the segmental strengthening ribs 16, said blocks having slotted lower sides and the horizontal semi-cylindrical seats 21, the bolt having the T-head to rest in one of said seats, the washer 26 to rest in the other seat and a locking nut on said bolt, substantially as described.

6. The combination with the rail or rails, of the tie-plate adapted to rest upon the cross-ties and provided with the integral trusses 5, 6, and 7 respectively, the separable angle-bar 10, the integral angle-bar 8 adapted to engage 60 the webs only, bolts for securing the same upon the rails, curved clamping blocks or jaws having clamping edges 18, and the fastening bolt therefor, substantially as described.

In testimony whereof I have hereunto set 65 my hand this 11th day of May, A. D. 1892.

FREDERICK H. HEATH.

In presence of—

C. G. HAWLEY,
FREDERICK S. LYON.
